US0D1018564S

(12) **United States Design Patent** (10) **Patent No.:** **US D1,018,564 S**
Lee et al. (45) **Date of Patent:** **** Mar. 19, 2024**

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Woonghee Lee**, Suwon-si (KR); **Younga Kim**, Suwon-si (KR)

(73) Assignee: **Samsung Electronics Co., Ltd.**, Suwon-si (KR)

(**) Term: **15 Years**

(21) Appl. No.: **29/829,370**

(22) Filed: **Mar. 4, 2022**

(30) **Foreign Application Priority Data**

Sep. 6, 2021 (KR) 30-2021-0042397

(57) **CLAIM**

We claim the ornamental design for a display screen or portion thereof with graphical user interface, as shown and described.

DESCRIPTION

The sole FIGURE is a front view of a display screen or portion thereof with graphical user interface showing our new design.

The outermost broken line in the figures depicts a display screen or portion thereof that forms no part of the claimed design.

The remaining broken lines showing portions of the graphical user interface form no part of the claimed design.
